CONTROL APPARATUS

Charles S. Powell, Wilkinsburg, Pa., assignor to
Westinghouse Electric Corporation, East Pitts-
burgh, Pa., a corporation of Pennsylvania

Application December 5, 1944, Serial No. 566,719

6 Claims. (Cl. 200—5)

1

My invention relates, generally, to control apparatus and has reference, in particular, to push-button control stations.

Generally stated, it is an object of my invention to provide an improved push-button control station that is simple and inexpensive to manufacture and easy to operate.

More specifically, it is an object of my invention to provide for so interlocking the buttons of a push-button station as to provide a slip contact which may be used to set up an alarm circuit for a circuit breaker whenever it is tripped automatically but not when it is tripped manually.

Another object of my invention is to provide for readily adapting standard designs of push-button stations for operation in circuit breaker control systems.

Another object of my invention is to provide for locking one push button on a push-button station in an intermediate position, and for releasing it to a predetermined operating position upon operation of another push button of the station.

A further object of my invention is to provide for adapting a pair of standard push-button elements for operation in interlocked relation.

It is also an important object of my invention to provide for adding a movable interlocking member to a standard push-button station so as to normally maintain one of the push buttons in an intermediate operating position until another of the push buttons is operated.

Other objects will in part be obvious, and will in part be described hereinafter.

In accordance with my invention, the operation of a pair of standard push-button elements, which are spring biased to the non-operated position, may be interlocked by means of a slidable interlocking member, which is normally biased to move a portion thereof into interference with one of the push buttons so as to hold it in an intermediate operating position from which it may be manually operated to the operating position only. Upon operation of the other push button, an inclined surface of the interlocking member is engaged thereby so as to actuate the interlocking member to free the other push button, which then returns to the non-operated position.

For a more complete understanding of the nature and scope of my invention, reference may be made to the following detailed description which may be studied in connection with the accompanying drawing, in which:

Figure 1 is a side elevational view in section of a push-button station embodying the invention in one of its forms;

2

Fig. 2 is a side elevational view in section of the push-button station shown in Fig. 1 with one of the push buttons retained in an intermediate operating position by the interlocking member;

5 Fig. 3 is a plan view of the interlocking member;

Fig. 4 is a partial side elevational view of a push-button station embodying the invention in another of its forms;

10 Fig. 5 is an end elevational view of the push-button station shown in Fig. 4;

Fig. 6 is a plan view, broken out in part, of the interlocking member used with the push-button station shown in Figs. 4 and 5; and

15 Fig. 7 is a diagrammatical view of a circuit breaker control system illustrating an application of a push-button station embodying the invention.

Referring to Figures 1 and 2, the reference numerals 10 and 11 may denote, generally, similar 20 push-button elements of a well-known design, which are disposed to be mounted on a base or cover member 12 having openings 14 and 15 for receiving the operating portions of the push buttons 16 and 17, respectively.

25 The push-button elements may be of any suitable design comprising, for example, body or housing members 18 of insulating material wherein may be slidably supported means such as the pins 19 upon which movable contact or bridge mem-

30 bers 20 and 21 may be supported for engaging pairs of stationary contact members 10a, 10b and 11a, 11b. Operation of the contact members may be effected by means of the push buttons 16 and

35 17 which may be secured to the pins 19 in any suitable manner, and provided with enlarged shoulder portions 24 and 25 positioned within openings 26 and 27 in the body members. The contact members 20 and 21 may be normally biased into engagement with the stationary contact members 10a and 11a by means of springs

40 28 mounted within the body members. Openings 30 and 31 may be provided in one side of the body members for gaining access to the shoulder portions of the push buttons, for a reason

45 which will hereinafter be explained in detail.

In order to provide, in effect, a slip contact such as may be used in controlling the operation of a circuit breaker or the like, means such as the movable interlocking member 32 may be pro-

50 vided for controlling the operation of one of the push buttons, for example, the push button 16. As shown in Figs. 1, 2 and 3, the interlocking member 32 may comprise, generally, a relatively thin plate 34 which may be slidably positioned be-

55 tween the push-button elements and the base or

cover which may be positioned in spaced relation by projections 33 or by means of brackets 35 shown in Figs. 4 and 5. The plate may be provided with elongated spaced openings 36 and 37 therein for receiving the projecting portions of the push buttons 16 and 17 so as to allow longitudinal movement of the plate relative thereto.

In order to control the operation of the push button 16, suitable means may be provided on the plate 34 for projecting into the opening 30 of the element 10 to interfere with the shoulder portion 24 of the push button 16. For example, a projection or a button 38 may be provided adjacent one end and disposed to be positioned between the shoulder portion 24 and the cover 12 when the push button 16 is operated. Means such as the spring 39 may be provided for normally biasing the interlocking member to bring the projection 38 into interference with the shoulder portion 24.

Release of the push button 16 to the non-operated position may be effected by providing for movement of the interlocking member to free the projection 38 from the shoulder portion 25 whenever the push button 16 is operated. For example, a projection or abutment 40 may be provided on the plate 34 having an inclined surface portion 41 for projecting into the opening 30 in the push-button element 11 to effect engagement with the enlarged shoulder portion 25 of the push button 16. The projection 40 may also be provided with a recess 42 for receiving one end of the spring 39 so as to maintain it in operating relation with the housing of the push-button element 10.

With the push-button station in the operating position shown in Fig. 1, the push button 17 may be operated without effecting the position of the push button 16, and it will return to the non-operated position upon release. However, when the push button 16 is operated to bring the contact member 20 into engagement with the stationary contact members 10b, the spring 39 forces the interlocking member 32 to the left as soon as the shoulder portion 24 of the push button 16 clears the projection 38. Upon release, the push button 16 can only return to an intermediate operating position, as shown in Fig. 2, by reason of the projection 38 being in interference with the shoulder portion 24. Release of the push button 16 to the non-operated position may be effected by operating the push button 17. Upon engagement of the shoulder portion 25 with the inclined surface 41 of the projection 40, the interlocking member 32 is actuated against the force of the spring 39 and toward the right, thus freeing the projection 38 from the shoulder portion 24 of the push button 16. The push button 16 returns to the non-operated position by reason of the spring 28.

Referring to Figs. 4 and 5, it may be seen that the push-button elements 10 and 11 are substantially identical with the elements 10 and 11 of Figs. 1 and 2 and have corresponding parts identified by the same numerals used in Figs 1 and 2. The elements 10 and 11 may be secured to the base or cover member 12 by means of screws 44 which extend through the body members of the elements and are threaded into the inturned portions 45 of the brackets 35 secured to the base member.

Since openings are thereby provided by the inturned portions 45 of the brackets and the body portions thereof, use may be made of these openings for supporting an interlocking member instead of positioning the member in the manner

described in connection with Figs. 1 and 2. For example, the interlocking member may comprise a substantially open frame having spaced apart side members 47, which may be slidably positioned in the openings provided between the inturned portions 45 of the brackets and the body portions thereof.

The side members may be maintained in spaced relation by means of end members 48 and 49 secured thereto in any suitable manner, and an intermediate transverse member 50 as shown in Fig. 6. If desired, the side and end members may be formed integrally, such as by punching them out of a piece of plate metal or the like. A projection 51 may be provided on one end member for engaging the shoulder portion 24 of the push button 16 to maintain it in an intermediate position after operation in a manner similar to that described in connection with Figs. 1 and 2.

Means such as the projection 52 may be provided on the intermediate transverse member 50 having a sloping surface portion 53 for engagement by the shoulder portion 25 of the push button 17 for actuating the interlocking member to free the projection 51 from the shoulder portion 24 of the push button 16.

Means such as the spring 55 may be provided for normally biasing the interlocking member to cause interference of the projection 51 with the shoulder portion of the push button 16.

Operation of the push-button station shown in Figs. 4, 5 and 6 is substantially identical with that described in connection with the push-button station of Figs. 1, 2 and 3. Accordingly, details of the push-button construction have been purposely omitted in Figs. 4 and 5 in the interests of simplicity, and only the outlines thereof are shown.

Referring to Fig. 7, the reference numeral 60 may denote, generally, a circuit breaker having contact members 60a for controlling the energization of a load 61 from a source such as the generator 62. The circuit breaker may be of any suitable type having, for example, an operating mechanism comprising a solenoid 64 having an operating winding 65 and operatively connected to the circuit breaker contact members through a lever mechanism 66 provided with latching members 67 and 68. Means such as the trip device 69 may be provided for releasing the latch member 68 to open the circuit breaker upon energization of the trip winding 70.

Energization of the circuit breaker operating winding 65 may be effected under the control of a control relay 72 having an operating winding 73 for actuating a toggle armature mechanism 74 to close contact members 72a, and a release winding 75 for actuating the armature 74 to open said contact members. The operating and release windings may be so disposed that when the release winding 75 is connected in parallel with the operating winding 73, it is sufficiently strong enough and has a sufficiently low impedance so as to weaken the energization of the operating winding 73 to cause operation of the armature 74 to open contact members 72a.

Operation of the control relay 72 may be effected by means of a push-button station having a push button 16 with normally open contact members 11b for connecting the operating winding 73 to the source. Normally closed contact members 11a of the push button 17 may be used to provide an energizing circuit for an alarm 77 in conjunction with normally closed contact members 10a of the push button 16. Normally

open contact members 10b may be provided for effecting energization of the trip winding 70 when it is desired to trip the circuit breaker manually.

The circuit breaker 60 may be provided with suitable means, such as the current relay 78, for effecting energization of the trip winding 70 to open the circuit breaker whenever the load current exceeds a predetermined value.

In order to provide for operating the alarm 77 whenever the circuit breaker is tripped by the current responsive relay 78, the push buttons 16 and 17 may be provided with an interlocking member 32 of the nature described hereinbefore in connection with Figs. 1 through 6. With the circuit breaker in the closed position as shown, the circuit breaker may be tripped through operation of the current responsive relay 78 which provides an energizing circuit for the trip winding 70 extending through the circuit from the conductor 80 through contact members 78a, conductor 81, contact members 60b of the circuit breaker trip winding 70, back to the source through conductor 82.

As soon as the circuit breaker opens, an energizing circuit is provided for the alarm 77 to the circuit extending from the conductor 80, through conductor 83, contact members 10a, contact members 11a, contact members 60a, alarm 77, back to the source through conductor 82.

Reclosure of the circuit breaker may be effected by depressing the push button 17 so as to complete an energizing circuit of the operating winding 73 of the control relay, through contact members 11b of the push button 17. The armature 74 is thereby actuated to close contact members 72a and provide an obvious energizing circuit for the operating windings 65 of the circuit breaker.

Immediately upon closure of the circuit breaker, an energizing circuit is provided for the release winding 75 of the control relay through contact members 60c of the circuit breaker in parallel circuit relation with the operating windings 73. The release winding 75 overcomes the operating winding 73 so that the armature 74 is actuated to open contact members 72a and effect deenergization of the circuit breaker operating winding 65.

The circuit breaker may be tripped manually by operating the push button 16 to provide an energizing circuit for the trip winding 70 through contact members 10b. Upon operation of the push button 16, the interlocking member 32 moves to the left so that the projection 38 is positioned behind a shoulder portion 24 of the push button and prevents its return to the non-operated position. Accordingly, both contact members 10a and 10b will be open. When the circuit breaker opens and closes contact members 60a, energization of the alarm 77 is prevented since the alarm circuit is open at contact members 11a.

From the above description and the accompanying drawing, it will be apparent that I have provided, in a simple and effective manner, for adapting push buttons of standard design for operation in interlocked relation. According to the embodiments of my invention, a minimum of time and expense only are necessary in making the adaptation, and a suitable control station may thereby be provided for effecting operation of a circuit breaker.

Since certain changes may be made in the above-described construction, and different embodiments of the invention may be made without departing from the spirit and scope thereof, it is intended that all matter contained in the above

description or shown in the accompanying drawing shall be considered as illustrative and not in a limiting sense.

I claim as my invention:

5. A push-button station comprising, a plurality of push buttons operable against biasing means, one of said push buttons having a pair of different operating positions, and an interlocking member normally biased in one direction to interfere with said one of the push buttons and retain it under the action of said biasing means in an operating position intermediate said different operating positions after operation, said member being operable in the opposite direction to release said push button from said intermediate position in response to operation of another of the push buttons.

2. A push-button station comprising, a pair of push-button elements each having a push button biased to one position and operable to another position, a slidable interlocking member having a portion interfering with one of the push buttons to retain it in an intermediate position between said one position and said another position after operation and a portion interfering with the other push button for actuating the member out of interference with the one push button upon operation of the other push button, and means biasing the interlocking member to 30 move the portion into interference with said one push button.

3. A push-button station comprising, a base member, a pair of push-button elements each having associated normally open and normally closed contact members operable by push buttons projecting through the base member, an interlocking member positioned adjacent the base member having a shoulder portion disposed to interfere with one of the push buttons to retain its elements in an intermediate operating position intermediate its normally open and normally closed contacts after operation and an additional shoulder portion disposed to engage the other push button when it is operated and actuate the 45 interlocking member to move the first-mentioned shoulder portion out of interference with said one push button, and means biasing the interlocking member to move the first-mentioned shoulder portion into interference with the said 50 one push button.

4. In a push-button station, an elongated support, a pair of push-button elements mounted on the support and having contact means actuatable to different operating positions by push buttons 55 projecting through the support and having enlarged shoulder portions to the rear thereof, a plate member slidably positioned between the push-button elements and the support, said plate member having an abutment disposed to interfere with the shoulder portion of one of the push buttons to retain the one push button in an operating position intermediate said different operating positions and an additional abutment having an inclined surface disposed to engage 60 the shoulder portion of the other button and actuate the plate member to free the first-mentioned abutment from interference with the shoulder portion of said one push button, and means biasing the plate member to move the first-mentioned abutment into interference with the shoulder portion of said one push button.

5. In a push-button station, a pair of push-button elements each having a housing with contact members positioned therein biased to one 75 operating position and operable to another op-

erating position by push buttons having enlarged shoulder portions within the housings with operating portions of reduced sections projecting therefrom, an elongated base member having an opening for each of the projecting push-button portions, bracket means secured to the base member and having inturned end portions spaced from the base member for receiving retaining means for securing each of the push-button elements to the base member, an interlocking member slidably supported between the base member and the push-button elements by the inturned end portions of the bracket means and having a portion for interfering with the shoulder portion of one of the push buttons to retain it in an intermediate position between said operating positions after operation and an additional portion having an inclined surface portion for engaging the shoulder portion of the other push button upon operation of said other push button to move the first-mentioned portion out of interference with the shoulder portion of said one push button, and means biasing the interlocking member to move said first-mentioned portion into interference with the shoulder portion of said one push button.

6. A control system for a circuit breaker having an operating winding and a trip winding comprising, means operable to energize the trip winding in response to a fault condition in a circuit controlled by the circuit breaker, a circuit breaker having an operating winding for operating the relay to effect energization of the circuit

breaker operating winding and a release winding for operating the relay to deenergize the circuit breaker operating winding, an alarm bell, and a push-button station having a pair of push-button elements with movable contact members normally biased by spring means one operating position to provide an energizing circuit for the alarm when the circuit breaker is tripped by the fault responsive means, said contact members being respectively operable to different operating positions to provide for energization of the circuit breaker relay operating winding and the trip winding, and interlock means normally actuatable in response to operation of the operating winding push button operable to retain the trip winding push button in an intermediate non-operating position after it has been operated to energize the trip winding, whereby the energizing circuit for the alarm is interrupted, said interlock means being actuatable upon operation of the circuit breaker relay push button to free the trip winding push button from the intermediate position.
